UNITED STATES PATENT OFFICE

EDGAR W. HEISEY, OF NEWARK, OHIO, ASSIGNOR TO A. H. HEISEY & COMPANY, OF NEWARK, OHIO, A PARTNERSHIP

HOLDER FOR CANDLES

Application filed January 30, 1928. Serial No. 250,659.

My invention relates to a holder for candles. It has to do, particularly, with a novel combination of a receptacle and a closure therefore, with the closure specially designed to be both effective as a closure and to constitute a support for a candle.

One of the features of my invention consists in the fact that it comprises a receptacle which may be filled or partially filled with colored material of any type. Another feature of my invention consists in the fact that a fluid-tight stopper is provided. Another feature of my invention resides in the fact that a stopper is provided with a socket for the reception of a candle and with an apron to protect the receptacle from dropping candle grease. My entire structure is preferably designed to simulate, in a general way, a common type of candle holder.

The preferred embodiment of my invention is shown in the accompanying drawings wherein similar characters of reference designate corresponding parts and wherein:

Figure 1 is a perspective view of my holder for candles.

Figure 2 is a vertical sectional view of the structure shown in Figure 1.

In the drawings, I have shown my candle holder as comprising a receptacle 1 which is preferably of the general form shown. It will be apparent that this form of receptacle is a more or less fanciful simulation of the base or dish portion of a common type of candle holder.

This receptacle portion 1 is provided with a neck 2 having an opening 3 therethrough. Adapted to be placed in this opening, is a closure member having a stopper portion 4. Formed integrally with this stopper portion and extending upwardly therefrom is a socket portion 5 having a socket 6 formed therein.

The socket portion of the closure member is preferably formed with an upwardly and downwardly flared apron. This apron is of graceful curvature and is effective to catch any drippings from the candle under all normal conditions of use.

The stopper portion 4 of the closure member is separated from the socket portion 5 of this member by an inwardly curved waist 7.

The size and curvature of this waist portion and of the socket portion thereabove is such that it lends itself readily to encircling by the fingers of the hand in the transporting of the closure member from one place to another.

In practice, the socket 6 of the socket member 5 is intended to receive a candle of any form. The receptacle 1 may be filled or partially filled with a colored liquid or powder or may be given additional ornamentation or distinctive appearance in any desired manner. The receptacle 1 is preferably of blown glass and the closure member is preferably of pressed glass.

One of the advantages of my invention arises from the fact that the stopper of the closure member has a "ground-in" fit in the neck of the receptacle and is therefore fluid-tight. Another advantage of my invention consists in the fact that this closure member may be transported from place to place independently of the receptacle and with a candle in the socket thereof. Furthermore, the closure member is of a size and contour to facilitate grasping and carrying, while the candle is in its socket and burning and, during such carrying, the integrally formed apron adequately protects the hand of the holder from drippings from the candle under all normal conditions of transportation. Likewise, this apron will have the effect of absorbing color rays, either from the colored material in the receptacle or from the candle light or from other sources.

It will be seen that I have provided a candle holder which is shaped to construct and which lends itself readily to ornamentation. It will also be apparent that it has certain advantageous structural features which are simple and graceful and which also contribute to the utility of the candle holder whether its parts be used separately or together.

Having thus described my invention, what I claim is:

1. In a candle holder, a base which takes the form of a glass receptacle, and a closure for said receptacle having a socket therein for the reception of a candle, said closure

having a shank curved to fit the fingers of the hand.

2. In a candle holder, a base which takes the form of a glass receptacle, and a closure for said receptacle having a socket therein for the reception of a candle, and an apron carried by said closure.

3. A closure for a receptacle comprising a socket member adapted to receive a candle, a shank curved to fit the fingers of the hand, and an apron surrounding said socket member.

In testimony whereof I, hereby affix my signature.

EDGAR W. HEISEY.
